UNITED STATES PATENT OFFICE.

THOMAS H. FURMAN, OF DENVER, COLORADO.

HAIR-DRYING COMB.

No. 899,038.

Specification of Letters Patent. Patented Sept. 22, 1908.

Application filed October 8, 1907. Serial No. 396,456.

To all whom it may concern:

Be it known that I, THOMAS H. FURMAN, citizen of the United States, residing at Denver city, county of Denver, and State of Colorado, have invented certain new and useful Improvements in Hair-Drying Combs, of which the following is a specification.

This invention is designed to provide a comb specially adapted for drying the hair and which may be fitted to a curling iron or like device adapted to be heated, so as to impart, by conduction, its heat to the comb for driving off dampness or moisture from the hair as the comb is passed therethrough. For a full understanding of the invention and the merits thereof and also to acquire a knowledge of the details of construction and the means for effecting the result, reference is to be had to the following description and accompanying drawings.

While the invention may be adapted to different forms and conditions by changes in the structure and minor details within the scope of the appended claims without departing from the spirit or essential features thereof, still the preferred embodiment is shown in the accompanying drawings, in which:

Figure 1 is a perspective view of a comb embodying the invention, showing the same fitted to a curling iron of ordinary formation. Fig. 2 is a perspective view of the comb. Fig. 3 is a top plan view of the comb, bringing out more clearly the clamp by means of which it is secured to the curling iron or like element. Fig. 4 is an end view of the comb.

Corresponding and like parts are referred to in the following description and indicated in all the views of the drawings by the same reference characters.

The comb is essentially of metal and may be of any size, design or manufacture, and is provided along its back with an opening in which the curling iron or like device is fitted. The hollow or tubular back 1 is split or formed with an opening 2 adjacent to the body of the comb to admit of the heat radiating directly from the iron 3, thereby hastening the operation of drying the hair when the comb is in use. The opening 2 also admits of the back 1 yielding so as to adapt itself to variations in the size of the curling iron or like device to which the comb may be fitted. In the preferable construction, the comb is constructed of sheet metal, one edge being

cut to provide the teeth and the opposite edge rolled to form a hollow or tubular back 1 designed to receive the device to which the comb is fitted. Clamp members 4 extend from one end of the hollow back 1 in line therewith and are adapted to grip the device to which the comb is fitted so as to retain it in place. The clamp members 4 are an integral part of the sheet metal blank from which the comb is formed. The outer end portions of the clamp members 4 flare slightly to facilitate the entrance of the iron or other device 3 when placing the comb in position to be slipped thereon.

Inasmuch as the comb is designed for use in connection with a curling iron, it is shown so applied, the iron and coöperating clamp being inserted in the space of the hollow back 1. The clamp members 4 embrace opposite sides of a handle member of the iron adjacent to the pivot connection of the two members, the contracted end portions formed by the flared terminals closing in the rear of the handle member so as to prevent outward displacement of the comb when slipped upon the iron. When using the comb, the iron is first heated, after which it is slipped into the opening or space formed in the hollow back 1 when the heat by the well known principle of conduction will be distributed throughout the comb and when passing the latter through the hair, the moisture or dampness thereof will be driven off.

Having thus described the invention, what is claimed as new is:

1. A metallic comb having a hollow back adapted to receive a heated iron, said hollow back being longitudinally split to provide for contraction and expansion to adapt the back to receive heated irons varying in size.
2. A metallic comb provided at one end with a spring clamp for securing the same to an iron or like device.
3. A metallic comb having a hollow back to receive an iron and having a spring clamp at one end of the hollow back and in line therewith to secure the comb upon the iron or like device.
4. A metallic comb having a hollow back longitudinally split throughout its length to enable the same to contract or expand and provided at one end with complementary spring clamp members, whose outer terminals flare.
5. As a new article of manufacture, a comb

formed of sheet metal having teeth along one end and having its opposite edge rolled to form a hollow back and having oppositely disposed spring clamp members in line with the back to secure the comb upon an iron or like device slipped into the space formed in the back of said comb.

In testimony whereof I affix my signature in presence of two witnesses.

THOMAS H. FURMAN. [L. s.]
